ANTICONVULSANT SUCCINIMIDE

Charles A. Miller, Detroit, and Loren M. Long, Grosse Pointe Woods, Mich., assignors to Parke, Davis & Company, Detroit, Mich., a corporation of Michigan
No Drawing. Filed Oct. 27, 1958, Ser. No. 769,582
9 Claims. (Cl. 167—65)

The present invention relates to anticonvulsant compositions useful in the treatment of epilepsy, and to methods for the prevention of convulsions and epileptic attacks by the use of these compositions.

More particularly, the present invention relates to therapeutic compositions which contain as an active ingredient α -ethyl- α -methylsuccinimide of the formula

and to methods for the use of such therapeutic compositions.

The compositions and methods of this invention are characterized by their high therapeutic effect with freedom from undesirable side-effects, by their ability to control epileptic seizures not amenable to other forms of therapy, and by their continued effectiveness when they are employed over prolonged periods of time. In these respects the present invention provides substantial advantages over the prior art.

It is known that epilepsy is a pathological condition involving the central nervous system. This condition is arbitrarily divided into three main types according to the type of seizure which takes place in the patient. These types include grand mal, petit mal, and psychomotor seizures. A patient may have any of the above seizures or a mixture of any of the types.

Experimentally, the effectiveness of a drug for protection against grand mal seizures is determined by its ability to raise the electroshock threshold in animals (usually mice or cats). The effectiveness of a product against petit mal seizures is determined experimentally by the use of the so-called anti-pentamethylenetetrazole test or anti-Metrazol $\circledR$ test which is based on the fact that the epileptic foci which give rise to petit mal attacks are situated in the region where pentamethylenetetrazole exerts its convulsive activity. Consequently, a product which will prevent seizures caused by pentamethylenetetrazole will also prevent a great many of the petit mal type of seizures. There is no satisfactory experimental method for the testing of drugs possessing the ability to control psychomotor seizures.

In the human patient the products used in the treatment of epilepsy are evaluated by their ability to reduce or control the number of seizures because these drugs function as prophylactics against the symptoms of this malady rather than act as curative agents. In the clinical evaluation of these products the type of seizures, the percent of the seizures controlled and the toxic manifestations of the product are taken into consideration.

The grand mal type of seizure has been treated with some success with 5-substituted phenylhydantoin such as 5,5-diphenylhydantoin but these compounds have little effect on the petit mal and psychomotor types of seizures.

Petit mal seizures have been treated with substituted 2,4-oxazolidinediones such as 3,5,5-trimethyl-2,4-oxazolidinedione (trimethadione). However, the usefulness of this drug is limited because of the high incidence of side-reactions such as photophobia, drug rash and leukopenia which attend its use.

More recently, a high degree of success has been

achieved in the treatment of petit mal seizures by the use of selected succinimides. Certain members of the succinimide series such as N-methyl- α -phenylsuccinimide and N-methyl- α -methyl- α -phenylsuccinimide have achieved wide acceptance in clinical medicine by virtue of their high therapeutic activity with minimal side-effects. However, the known succinimide therapeutic compositions, while they have in many cases achieved high levels of success in the prevention and control of petit mal seizures, have in other cases failed to produce a satisfactory result.

Thus, while it can be said that N-methyl- α -phenylsuccinimide and N-methyl- α -methyl- α -phenylsuccinimide are drugs of choice in the present-day treatment of epilepsy by virtue of their significant therapeutic effect with minimal toxicity in a majority of petit mal cases, it is nevertheless true that a substantial residuum of petit mal cases remains unbefited by these drugs or by any other known form of treatment. Furthermore, the drugs which are presently used in the treatment of epilepsy, including both succinimide and non-succinimide compositions, possess the general disadvantage of failing to maintain their initial therapeutic effect over a prolonged period of medication. That is, many cases are found where a particular patient initially obtains a complete prevention or substantial reduction in petit mal seizures on a particular medication, but, after continuation of the medication over a period of a few months or a few years, the effectiveness of the drug is substantially diminished. To the extent that drugs presently used in the treatment of epilepsy are incapable of maintaining their full effectiveness over a prolonged period of time they are deficient in the properties desired in a product of this type since epilepsy is a chronic condition which must be treated over a period of years.

One of the objects of the present invention is to provide compositions for the treatment of the petit mal type of epilepsy which are more effective than the compositions now in use for this purpose, and to provide compositions for the treatment of other types of epileptic seizures, both alone and in combination with petit mal seizures.

Another object of this invention is to provide compositions for the prevention of epileptic seizures which are therapeutically effective in cases where the known anticonvulsants, including the presently accepted succinimide compositions, have failed to produce clinically satisfactory results.

A further object of the invention is to provide compositions for the prevention of epileptic seizures which retain a high degree of effectiveness and continue to produce an adequate therapeutic response over a prolonged period of medication.

Still another object of this invention is to provide methods for the prevention of epileptic seizures by the use of α -ethyl- α -methylsuccinimide.

In accordance with the invention, these as well as other objects which will appear hereinafter are realized by the manufacture and use of compositions containing α -ethyl- α -methylsuccinimide, alone or in combination with other ingredients.

α -Ethyl- α -methylsuccinimide is known in the prior art as a chemical entity, having been prepared according to the method described by Sircar, J. Chem. Soc., 128:600 (1927), and characterized in J. Chem. Soc., 128:1254 (1927). However, its efficacy as a therapeutic agent has heretofore been unknown.

The high degree of effectiveness of α -ethyl- α -methylsuccinimide in controlling petit mal seizures can be demonstrated by results reported by Zimmerman and Burge-meister on a group of 109 cases of petit mal epilepsy. For the most part, this group of cases consisted of patients who had not responded satisfactorily to the other anticonvulsant drugs. Medication was administered initially at a dose of 250 to 500 mg. per day with a gradual in-

crease in the dosage over a period of weeks until the optimal effect was achieved or toxic side-effects intervened. The average daily dose for this group of patients was 1.75 g. The results obtained are summarized in Table 1.

TABLE 1

Effectiveness of α -ethyl- α -methylsuccinimide in controlling or reducing petit mal attacks in a group of 109 patients generally resistant to drug therapy

	No. of Patients	Percent of Patients	Avg. duration of Treatment (weeks)	Range of Control (weeks)	
Complete Control	46	42	44	12-96	15
Practical Control (80-99% reduction)	26	24	82	71-89	
Partial Control (5-79% reduction)	28	26	43	18-49	
No Effect (0-4% reduction)	7	6	34	20-43	
Worse (increase)	2	2	7	3-20	20

It is therefore seen that in this series of mostly intractable cases, complete control was secured in 42% of the patients, practical control was reached in an additional 24% and partial control in an additional 26% giving a total of 92% of all patients treated who received a measurable benefit from the drug.

Confirmation of the high activity of the α -ethyl- α -methylsuccinimide is found in a group of 20 cases reported by Strohos. These patients were afflicted with petit mal epilepsy alone and in combination with other types of seizures. Medication was administered to this group of patients at a dosage range from 0.75 to 2.0 g. per day. The results obtained are summarized in Table 2.

TABLE 2

Effectiveness of α -ethyl- α -methylsuccinimide in a group of 20 petit mal patients

Effect on Seizures	No. of Patients	Percent of Patients
Controlled	10	50
Substantially Controlled	3	15
Some Reduction	2	10
No Effect	5	25
Worse	0	0

In this group of cases, seizures were completely controlled in 50% of the patients, substantially controlled in an additional 15% and partially controlled in an additional 10% giving a total of 75% of all patients treated who received a significant benefit from the drug.

While these results demonstrate the high activity of α -ethyl- α -methylsuccinimide in preventing petit mal seizures, it is of even greater significance that patients who

are not benefited at all by presently-known anti-epileptic compositions can in favorable cases obtain complete prevention of petit mal seizures by the compositions and methods of this invention. There are summarized in Table 3 the results obtained with 7 patients (of the group of 109 cases compiled in Table 1) who had received no benefit from prior treatment with N-methyl- α -methyl- α -phenylsuccinimide or combinations of N-methyl- α -methyl- α -phenylsuccinimide with other medications, but were benefited by subsequent treatment with α -ethyl- α -methylsuccinimide.

TABLE 3

Degree of control achieved in petit mal cases receiving no help from N-methyl- α -methyl- α -phenylsuccinimide which responded favorably to α -ethyl- α -methylsuccinimide immediately thereafter

	N-methyl- α -methyl- α -phenylsuccinimide	α -Ethyl- α -methylsuccinimide		
		No.	Percent	No.
Complete Control	0	0	3	43
Practical Control (80-99% reduction)	0	0	2	28.5
Partial Control (5-79% reduction)	0	0	2	28.5
No effect (0-4% reduction) or Worse (increase)	7	100	0	0

It is therefore seen that whereas N-methyl- α -methyl- α -phenylsuccinimide and α -ethyl- α -methylsuccinimide are structurally related compounds, their pharmacological differences are not mere differences of degree, but rather are differences which set them apart as therapeutic agents.

The distinctive character of α -ethyl- α -methylsuccinimide as an anticonvulsive agent is also found in the studies of Strohos and of Hughes, both of whom find petit mal patients completely controlled by this form of therapy, who had benefited little or not at all by previously used anticonvulsive agents.

The relative effectiveness of α -ethyl- α -methylsuccinimide in patients having pure petit mal attacks or more complex syndromes can be demonstrated by Table 4 wherein there are summarized results reported by Zimmerman and Burgemeister in the same group of 109 cases reported in Table 1, but broken down into types. For the purpose of this classification, the following definitions are applied:

(1) Pure petit mal: that form of epilepsy which manifests itself in loss of consciousness only with no concomitant motor phenomena.

(2) Mixed petit mal: that form of epilepsy which manifests itself predominantly in transient loss of consciousness and minor motor phenomena.

TABLE 4

Relative effectiveness of α -ethyl- α -methylsuccinimide in the treatment of petit mal attacks in 109 patients having various classes of seizures

	Pure Petit Mal Only		Mixed Petit Mal Only		Pure Petit Mal and Grand Mal		Mixed Petit Mal and Grand Mal		Pure Petit Mal and Psychomotor		Pure Petit Mal, Grand Mal, and Psychomotor	
	No.	Percent	No.	Percent	No.	Percent	No.	Percent	No.	Percent	No.	Percent
Complete Control	11	61	5	21	17	59	9	35	2	29	2	40
Practical Control (80-99% reduction)	4	22	2	8.5	9	31	9	35	1	14	1	20
Partial Control (5-79% reduction)	3	17	14	58	2	7	3	11	4	57	2	40
No Effect (0-4% reduction)	0	0	2	8.5	1	3	4	15	0	0	2	0
Worse (increase)	0	0	1	4	0	0	1	4	0	0	0	0
Total	18		24		29		26		7		5	

It is seen from these results that α -ethyl- α -methylsuccinimide is more effective in the treatment of pure petit mal than in the treatment of mixed petit mal and certain other classes of seizures.

In a series of 56 patients, all of whom had been treated previously with other drugs with generally unsatisfactory results, Vossen has reported the superior activity and high selectivity of α -ethyl- α -methylsuccinimide on petit mal attacks. Strobo has likewise reported results which demonstrate the selective action of α -ethyl- α -methylsuccinimide on idiopathic and particularly petit mal seizures, but which indicate little effect on focal seizures or seizures resulting from brain damage. A classification of the 20 cases reported in Table 2 according to the type of seizure is summarized in Table 5.

TABLE 5

Relative effectiveness of α -ethyl- α -methylsuccinimide in the treatment of 20 patients having various classes of seizures including a petit mal component

	Petit Mal Only		Grand Mal and Petit Mal		Grand Mal and Petit Mal and Akinetic	
	No.	Percent	No.	Percent	No.	Percent
Controlled.....	6	60	3	42	1	33
Substantially controlled.....	2	20	1	14		
Some Reduction.....	2	20	1	14	1	33
No Effect.....			2	28	1	33
Total.....	10		7		3	

It is therefore observed that of the patients in this study afflicted with petit mal epilepsy only, 60% were controlled and free of seizures and an additional 20% were substantially controlled.

In common with succinimide compositions which have already been accepted in clinical medicine, α -ethyl- α -methylsuccinimide exhibits toxic side-reactions which are both infrequent and mild. Toxic side-effects were noted in only 10 of the group of 109 cases summarized in Table 1. These side-effects are shown in Table 6.

TABLE 6

Nature and incidence of toxic side-effects of α -ethyl- α -methylsuccinimide in a group of 109 patients

Side effect:	No. of patients
Drowsiness.....	4
Dizziness.....	2
Nausea.....	2
Gastric distress.....	2

It was further observed that toxic side-effects usually occurred on relatively high dosage levels and could be reduced or eliminated entirely by a reduction in dosage.

It has already been indicated that presently accepted anti-epileptic agents possess the common disadvantage that they fail to continue to produce their maximum therapeutic response when medication is continued over a prolonged period of time. In contrast, the administration of α -ethyl- α -methylsuccinimide is accompanied by an increasing effectiveness upon prolonged treatment. The opposite effects obtained with α -ethyl- α -methylsuccinimide and with other anticonvulsants including other succinimide compositions such as N-methyl- α -phenylsuccinimide and N-methyl- α -methyl- α -phenylsuccinimide are illustrated in Table 7.

TABLE 7

Effectiveness of anticonvulsant drugs upon prolonged medication

5	Complete Control for.....	6 mos., percent	1 yr., percent	1½ yrs., percent	2 yrs., percent
	Phenobarbital.....	22	17	11	8
10	Trimethadione.....	36	34	31	28
	N-methyl- α -phenylsuccinimide.....	30	27	24	21
	N-methyl- α -methyl- α -phenylsuccinimide.....	22	20	19	19
	α -ethyl- α -methylsuccinimide.....	28	34	39	42

In this table, the criterion for effectiveness of each drug is defined as the percentage of patients completely protected against seizures. It will be observed that for each of four standard anticonvulsants the percentage of patients so protected steadily drops as medication is continued for a period of up to two years whereas in the case of α -ethyl- α -methylsuccinimide the percentage of patients so benefited substantially increases over the same interval of time. It is again seen that α -ethyl- α -methylsuccinimide exhibits pharmaceutical properties which are differentiated in kind rather than in degree from other anticonvulsants.

According to the present invention, anticonvulsant compositions are produced by constituting α -ethyl- α -methylsuccinimide in dosage unit form with pharmaceutical carriers or diluents. Dosage unit forms for oral administration are particularly suitable and for this purpose the α -ethyl- α -methylsuccinimide can be incorporated into tablets, powders, capsules, solutions, suspensions and similar forms. The medicament can be incorporated with pharmaceutically-acceptable solid or liquid diluents. Solid carriers and diluents suitable for use include sugars such as lactose and sucrose; cellulose derivatives such as sodium carboxymethyl cellulose, ethyl cellulose, methyl cellulose, and cellulose acetate phthalate; gelatin (including hard and soft gelatin capsules); talc; corn starch; stearic acid and magnesium stearate. Liquid carriers and diluents suitable for use include vegetable oils such as peanut oil, cottonseed oil, sesame oil, olive oil, corn oil and oil of theobroma; polyethylene glycol; propylene glycol; glycerin; sorbitol; ethanol and water. The compound is quite soluble in water and aqueous solutions of approximately 20% concentration can be prepared. Suitable preservatives and flavoring agents can also be incorporated in such compositions. If administration by a parenteral route is desired, the medicament can also be prepared in solution or suspension in ampoule form by admixture with a liquid diluent. Other therapeutic agents and, in particular, other anticonvulsants can be incorporated with the α -ethyl- α -methylsuccinimide in these compositions.

The percentage of α -ethyl- α -methylsuccinimide in the compositions can be varied within wide limits. However, for practical purposes, it is desirable that this compound be present in a concentration of at least 5% and the most satisfactory compositions are those in which a much higher proportion of this ingredient is present.

According to the methods of this invention, α -ethyl- α -methylsuccinimide or compositions containing the same are administered for the prevention and control of epileptic seizures. The substances are commonly administered orally to provide a total daily dose of about 0.1 to 5.0 g. of the compound, optionally in divided portions. The dose is adjusted within the indicated range to the needs of the individual patient by first administering a daily dose of about 0.1 to 0.5 g. and then increasing the dose until satisfactory control of seizures is obtained or undesirable side-effects intervene. In terms of individual patients, a satisfactory daily oral dose is usually found within the range of 5 mg. to 100 mg. per kg. of body weight.

In the preparation of dosage unit forms such as tablets and capsules, the quantity of medicament furnished by each individual tablet or capsule is relatively unimportant since the indicated total daily dose can be reached by administering either one or a plurality of the tablets or capsules. However, for convenience in manufacturing and ease of administration it is preferable that such dosage forms contain at least 25 mg. and up to 500 mg. of α -ethyl- α -methylsuccinimide per unit.

The invention is illustrated but not limited by the following examples:

EXAMPLE 1

α -Ethyl- α -methylsuccinimide is constituted into 500 mg. dosage units by encapsulation without an adjuvant into hard gelatin capsules. The yield from 1,000 g. of α -ethyl- α -methylsuccinimide is about 1980 capsules, each containing 0.5 g. of medicament.

EXAMPLE 2

An intimate mixture of 750 g. of α -ethyl- α -methylsuccinimide and 750 g. of powdered milk sugar is constituted into dosage unit form by encapsulating the mixture in 0.5 g. portions into hard gelatin capsules. The yield is about 2970 capsules each containing 250 mg. of α -ethyl- α -methylsuccinimide. If desired, the mixture can also be encapsulated in the so-called soft gelatin capsules. Also, if desired, the hard gelatin capsules can be sealed with a band of gelatin or other adhesive material.

EXAMPLE 3

A tableting formulation is prepared as follows:

540 grains α -ethyl- α -methylsuccinimide
5 ounces, 87 grains powdered sugar with 3% starch
7 grains sodium saccharin U.S.P.
500 grains corn syrup
q.s. water
88 grains talc U.S.P. powdered Italian
18 grains magnesium stearate
q.s. alcohol
8 min. oil spearmint terpeneless

The formulation is compressed into tablets each containing 100 mg. of α -ethyl- α -methylsuccinimide. The yield is about 320-350 tablets.

EXAMPLE 4

A tableting formulation providing a smaller dosage unit is prepared as follows:

162 grains of α -ethyl- α -methylsuccinimide
5 ounces, 87 grains powdered sugar with 3% starch
7 grains sodium saccharin U.S.P.
500 grains corn syrup
q.s. water
88 grains talc U.S.P. powdered Italian
18 grains magnesium stearate
q.s. alcohol
8 min. oil spearmint terpeneless

This formulation is compressed with a tableting machine to form tablets each containing 30 mg. of α -ethyl- α -methylsuccinimide. The yield is about 320-350 tablets.

EXAMPLE 5

α -ethyl- α -methylsuccinimide (500 g.) is dissolved in 12 liters of water following which 4,000 g. of sucrose and 2,000 g. of sorbitol are dissolved in the solution. Oil of orange (30 ml.) and sodium benzoate (20 g.) are then added. The resulting solution is filtered, diluted to 20 liters with water and filled into bottles each containing 100 ml. This aqueous solution, which is suitable for oral administration, contains 25 mg. of α -ethyl- α -methylsuccinimide per ml.

This is a continuation-in-part of copending application Serial No. 311,798, filed September 26, 1952, now abandoned.

What is claimed is:

15. 1. A composition in dosage unit form for the treatment of epilepsy comprising about 25 to 500 milligrams of α -ethyl- α -methylsuccinimide per dosage unit and a pharmaceutical carrier.
20. 2. A composition in dosage unit form for the treatment of epilepsy comprising about 25 to 500 milligrams of α -ethyl- α -methylsuccinimide per dosage unit and a liquid pharmaceutical carrier.
25. 3. A composition in dosage unit form for the treatment of epilepsy comprising a gelatin capsule containing about 25 to 500 milligrams of α -ethyl- α -methylsuccinimide.
4. A composition in dosage unit form for the treatment of epilepsy comprising a solid pharmaceutical carrier and about 25 to 500 milligrams of α -ethyl- α -methylsuccinimide per dosage unit.
30. 5. A tableted composition in dosage unit form for the treatment of epilepsy comprising a solid pharmaceutical carrier and about 25 to 500 milligrams of α -ethyl- α -methylsuccinimide per dosage unit.
35. 6. An encapsulated composition in dosage unit form for the treatment of epilepsy comprising a solid pharmaceutical carrier and about 25 to 500 milligrams of α -ethyl- α -methylsuccinimide per dosage unit.
40. 7. A method for the treatment of petit mal epilepsy which comprises administering α -ethyl- α -methylsuccinimide to a human patient.
45. 8. A method for the treatment of petit mal epilepsy which comprises administering α -ethyl- α -methylsuccinimide to a human patient in a daily oral dose of from 100 milligrams to 5 grams.
50. 9. A method for the treatment of petit mal epilepsy which comprises administering a composition comprising not less than five percent of α -ethyl- α -methylsuccinimide to a human patient in a daily oral dose which provides from 100 milligrams to 5 grams of the said α -ethyl- α -methylsuccinimide.
